UNITED STATES PATENT OFFICE.

EDWIN J. MURPHY, OF SCHENECTADY, NEW YORK, ASSIGNOR TO GENERAL ELECTRIC COMPANY, A CORPORATION OF NEW YORK.

ARC LAMP.

Application filed April 6, 1925. Serial No. 20,927.

My invention relates to arc lamps, and in particular to the feeding mechanism for such lamps. Among the objects of my invention are the following: To provide a feeding mechanism by means of which an electrode may be fed by two independent mechanisms at two different rates; to provide a feeding mechanism adapted to feed an electrode by two independent mechanisms at two different rates, one rate being under electromagnetic control so that this feeding rate may be suspended or continued without acceleration; to provide means for feeding an electrode at two different rates, one without acceleration and one intermittent, and electromagnetic means for controlling the feeding at one rate and electromagnetic means for controlling the feeding at a different rate; to provide a feeding mechanism with means for feeding at two different rates and with electromagnetic means and also with independent mechanical means for controlling one rate of feeding so as to suspend or continue without acceleration this rate of feeding, and to provide other means for increasing the efficiency and serviceability of an arc lamp of the above character.

To the foregoing and other useful ends my invention comprises means hereinafter more fully set forth and claimed, reference being had to the accompanying drawings in which Figure 1 shows an arc lamp, in elevation, comprising my invention; Fig. 2 is a diagrammatic illustration showing the relation of certain elements of the lamp for the purpose of facilitating an understanding of the invention; Fig. 3 shows the cam by means of which one of the feeding operations is produced. It also shows a section of the electromagnetically controlled mechanism, and a section of the manually controlled mechanism, by means of which the feeding is regulated; Fig. 4 is a bottom view of a section of the device shown in Fig. 1, and Fig. 5 is a diagrammatic sketch showing the relation of the electrodes and of the feed controlling magnets.

Referring more in detail to the drawings, and in particular to Fig. 1, the usual positive electrode 2 passes through the positive head 3, while the usual negative electrode 4 passes through the negative head 5. This latter head 5, it will be seen, is pivotally mounted to oscillate about the axis 6, as is well known. The feeding operation of the positive electrode 2 is produced through the medium of the shaft 7, while the feeding operation of the negative electrode 4 is produced through the medium of the shaft 8. As is well understood, the object in having the head 5 arranged to oscillate about the axis 6 is to enable the arc to be struck when the current is turned on. Normally, as is well understood, the head 5 is in a raised position in which position it is intended that the electrodes 2 and 4 should be in contact. When the current is turned on, the head 5 is caused to rotate about the axis 6 so that the electrode 4 leaves the electrode 2 thereby establishing the arc. This operation of the head 5 about the axis 6 is under the control of the rod 9. The normal relative position of the electrodes when the current is turned off is indicated in Fig. 5, in which figure the electrodes 4 and 2 are shown in contact. To turn on the lamp the switches 10 and 11 are closed and current will flow through the electrodes 4 and 2 and through the electromagnet 14. The result is that the armature 15 of the magnet is energized, pushing the rod upward to rotate head 5 in place thereof about the axis 6, thus establishing the arc. Also when the switches 10 and 11 are closed, the motor M is started, which motor supplies a power for operating the feeding mechanism. For example, the motor M is provided with a shaft having a worm gear 16 which meshes with the worm wheel 17 thereby rotating the shaft 18 with the result that through the medium of other suitable gears and shafts, the shaft 7 is rotated, thus rotating and feeding the positive electrode 2. On the shaft 18 there is also provided a cam 19 through the medium of which the negative electrode 4 is fed. Under the control of this cam 19 there is an arm 20 adapted to oscillate about the pin or other suitable bearing 21. On the forward end of the arm 20 there is a pawl 22 adapted to engage with the ratchet wheel 23. A compression spring 24 is provided for maintaining the dog 22 in engagement with the wheel 23. On the opposite end of the arm 20 there is provided a roller 25. This roller is adapted to be held against the surface of the cam 19 by the spring 26. Therefore, it will be seen that if the cam 19 rotates about the axis of the shaft 18 the arm 20 is caused to oscillate with the result

that the dog 22 through the medium of the wheel 23 causes the shaft 8 to rotate in the direction indicated by the arrow.

It will be observed that behind the roller 5 25 there is provided a pin 27. In proximity to this pin and in working relation thereto there is provided a spring 28. This spring is under the control of any suitable device such as the thumb screw 29. Through the 10 medium of this screw 29 it is possible to flex the spring 28 as indicated in Fig. 3 causing it to serve as a limiting stop for the arm 20. It will be seen, therefore, that when the spring 28 is raised as in Fig. 3 the advance produced in the shaft 8 at the stroke of the dog 22 is shortened inasmuch as the 15 pin 27 permits the arm 20 to approach toward the cam 19 only a limited distance.

In connection with this feeding mechanism for the negative electrode, I provide an electromagnetic device involving the electromagnet 30. This electromagnet, as indicated in Fig. 5, is connected across the electrodes 2 and 4. The result is that the 20 magnetic intensity of the field of this magnet depends upon the condition of the arc and upon the distance separating the electrodes 2 and 4. In this connection it will be observed that the cam 19 is provided with 25 a pin 31. In the path of rotation of this pin there is a stem 32 mounted on the dog 33 which is found on the armature 34 of the magnet 30. Normally the armature 34 is held away from the pole piece by the 30 spring 35. With the construction described, even if the magnet 30 is deenergized, the armature 34 is pressed against the pole piece once in each revolution of the cam 19. However, should the magnet 30 be energized then 35 when the armature 34 is pressed against the pole piece by the action of the pin 31, the armature will be held there against the tension of the spring 35 and therefore the dog 33 will be held out of the path of the catch 40 36 (see Fig. 4). As long as this magnet continues to hold the armature 34, the cam will continue to operate the arm 20 and the feeding operation of the negative electrode continues. However, if the electrodes 2 and 45 50 are brought into such proximity that the voltages across the electrodes is lowered below a certain point, the spring 35 will withdraw the armature 34 from the core with the result that the dog 33 will latch and hold the catch 36, thereby preventing and suspending the feeding operation. It will be understood that under these conditions the pin 31 at 55 each revolution will press the armature 34 against the core in opposition to the tension 60 of the spring 35. But the pin and the high point in the cam 19 and the roller 25 are so adjusted that the pin 31 will release the armature 34 before the catch 36 has had time to advance and escape the dog 33. However, at the moment that the magnetic pull 65

of the electromagnet 30 increases to such an extent as to be able to hold the armature 34 then even after the pin 31 leaves the stem 32 the armature 34 will be held and the arm 20 will be left under the control of the cam 19 so that the feeding operation will proceed.

It sometimes happens that the tip end of the negative electrode or possibly the tip end of the positive electrode is broken and that as a result the electrodes 2 and 4 are not in contact when the circuit is initially closed through the lamp. The result is that the electromagnet 14 does not energize and the arc is not struck and cannot be struck until the feeding operation produced by the motor M advances sufficiently to bring the two electrodes into contact. At this moment, of course, the magnet 14 energizes with the result that the arc is formed as already described.

If the only feeding mechanism provided were that already described under the control of the cam 19 and of the electromagnet 30 the feeding operation would be comparatively slow and considerable time might sometimes elapse before the arc would be started after the circuit is closed at the switches 10 and 11. In order to avoid this delay, which in many instances is very undesirable, I provide means for rapidly feeding the negative electrode in the event that the magnet 14 is not energized while the switches 10 and 11 are closed.

As already pointed out, the striking operation is under the control of the magnet 14 through the medium of the armature 15 and of the arm 9. By referring to Fig. 2, it will be seen that I provide on the shaft 18 a gear 37, which is feathered to slide on the shaft 18, but which cannot rotate without rotating the shaft 18. In operative relation with the gear 37 and on the shaft 8 upon which the ratchet wheel 23 is mounted, is a second gear 39 which is secured to the shaft 8. By this arrangement, whenever the gear 39 is rotated the feeding shaft 8 is also rotated. It will be seen that the gear 37 is under the control of the bifurcated arm 40, the prongs of which are in mesh with a groove on the hub of the gear 37. This arm 40 is so located that the rod 9 passes through a hole in the arm 40. The arm 40, it will be further seen, is pivoted to oscillate about the pin 41. Between the arm 40 and a section 42 of the frame of the lamp, I provide a compression spring 43 which tends normally to depress the arm 40 and also the armature 15 inasmuch as I provide a collar on the underside of the arm 40 secured to the shaft 9.

With the arrangement described when the magnet 14 is deenergized the gear 37 is depressed by the spring 43 into engagement with the gear 39. Therefore, if the switches 130

10 and 11 are closed and if the end of either electrode 2 or 4 is broken so that the electrodes are not in contact, the motor M will begin to operate but the electromagnet 14 cannot energize. The result is that the motor M will drive the shaft 18 and therefore the gears 37 and 39, and consequently the feed shaft 8, thereby producing a very rapid feed which will immediately bring the 10 two electrodes into contact. As soon as the circuit is closed between the electrodes, the magnet 14 energizes striking the arc and disconnecting the gears 37 and 39 and thus terminates the rapid feed. The rapid feed if desired may be made about fifty or sixty 15 times faster more or less than the regular average feed while the arc is burning. This rate of feed gives the electromagnet 14 sufficient time to act to disconnect the direct feed and leave the electrodes to the action of 20 the regulator feed.

It will be seen, therefore, that I provide an arc lamp with a driving motor which rotates the positive electrode and the negative electrode, and which provides power for feeding both the positive and the negative electrodes. In addition I provide means for quickly striking the arc in the event that the two electrodes are normally in contact 25 at the start. As described the negative electrode is fed forward by means of a mechanism driven by a ratchet wheel, the ratchet wheel in the preferred construction shown being connected to the feeding mechanism 30 and being provided with teeth engaged by a pawl, which pawl is continuously reciprocated by means of a cam, which cam is continuously driven by the driving motor of the lamp. This ratchet is adapted to propel the electrode forward at a speed considerably greater than the speed of consumption. 35

This lamp is made automatic by the provision of the electromagnet 30, which is connected across the arc. This magnet is adapted to attract its armature, which armature when held in the attracted position will allow the ratchet pawl to engage the ratchet wheel and thus feed the negative electrode. 40 When the voltage across the arc falls to the proper value, the armature of the magnet 30 will not be held by the electromagnet and thus the lamp will not feed. In order that the amount of work performed by the electromagnet 30 may be reduced to a minimum, the cam 19 is provided which regularly forces the armature against the pole piece and if the voltage across the regulating coil 30 is normal the magnet cannot hold the 45 armature. On the other hand, if the voltage is above normal value the armature will be held and the lamp will proceed to feed.

In order to regulate the voltage at which the lamp should operate the tension of the spring 35 is controlled by means of an ad-

justable screw 44, which screw is supported by any stationary element which may be a part of the frame of the lamp.

By the provision of the pin 27 and the spring 28 it is possible to limit the throw 70 of the ratchet to one or more teeth and thus regulate the feeding rate of the electrode. Furthermore, in case of failure of the magnet 30 or of the regulating spring 35, the spring 28 can be swung into place and the 75 lamp can continue to operate satisfactorily until an opportunity presents itself for restoring the electromagnet control. It will be seen also that by the provision of the gears 37 and 39 the high speed feed takes 80 place regardless of the step-by-step feed under the control of the magnet 30.

It will be seen, therefore, that one form of the invention comprises a feed for the negative electrode and means such as the 85 gears 37 and 39 for connecting the feed to the driving element, such as the motor M. The invention in one form also contemplates independent means such as the ratchet and gear mechanism 22 and 23 under the control 90 of the cam 19 for operating the feed at a rate substantially different from that obtained through the medium of the gears 37 and 39. It will also be seen that either of the means for driving the feed is under the 95 control of electromagnetic means in order that either means may be thrown into or out of operative condition. One of the electromagnetic means, of course, comprises the electromagnet 14 and the other electromagnet 100 30.

In Fig. 5 the magnet 30 is shown in series with a resistance 46. This resistance may be varied, the object of the resistance being to allow the minimum amount of current to 105 pass through the magnet 30 which will insure its effective operation.

Referring to Fig. 3 it will be seen that when the spring 28 is in the position indicated in said figure this spring serves as a 110 restricting element, not only to the member 20, but also to the armature 34 and, therefore, to the dog 33, through the medium of the pin 45, which depends from the dog 33. Therefore, when the spring is in the position 115 shown in Fig. 3, the dog 33 is rendered ineffective with reference to the notch 36 and, therefore, even though the magnet 30 be deenergized the feeding operation under the control of the cam 19 will continue. It 120 will be seen, however, that the stroke of the element 20 under the conditions shown in Fig. 3 is shorter than under the conditions shown in Fig. 2 inasmuch as when the spring 28 is allowed to fall below the pin 27, it also 125 falls below the range of the pin 45.

While I have shown in the drawings one form of embodiment of my invention, it will be understood that I do not wish to be restricted to the particular form shown in as- 130

much as in view of the disclosure variations may readily be made without departing from the spirit of my invention or from the scope of the claims contained herein.

5. What I claim as new and desire to secure by Letters Patent of the United States, is:—

1. In an arc lamp an electrode feed mechanism, a driving element, means interposed between the driving element and the feed 10 whereby the feed is operated by the drive at a rapid rate until the electrodes are brought into contact, and means comprising the electrodes of the lamp for causing the termination of said rapid feed when the electrodes 15 come into contact, and independent means interposed between the driving element and the feed whereby the feed is operated by the drive at a slow rate, said independent means comprising mechanical elements to render 20 the feeding operation intermittent.

2. In an arc lamp an electrode feed mechanism, a driving element, means interposed between the driving element and the feed mechanism whereby the feed may be operated 25 by said driving element, an electromagnetic device, said means under the control of said device whereby the feeding operation may be regulated, said device comprising an armature through the medium of which said 30 control is exercised sometimes by the magnet holding the armature against the pole piece and sometimes by the magnet releasing the armature, and means independent of the magnet for periodically forcing the armature 35 against the pole piece, and means for rendering the control of said feed through said armature ineffective, and at the same time maintaining the said interposed means effective whereby the feeding operation may 40 be continued without interruption by said armature.

3. In an arc lamp an electrode feed mechanism, a driving element, means interposed 45 between the driving element and the feed mechanism whereby the feed may be operated by said driving element, an electromagnetic device, said means under the control of said device whereby the feeding operation may be regulated, said device comprising an 50 armature through the medium of which said control is exercised by the magnet holding the armature against the pole piece or by releasing the armature, and means independent of the magnet for periodically pressing 55 the armature against the pole piece and withdrawing it therefrom.

4. In an arc lamp an electrode feed mechanism, a driving element, means interposed 60 between the driving element and the feed mechanism whereby the feed may be operated by said driving element, an electromagnetic device, said means under the control of said device whereby the feeding operation may be regulated, said device comprising an 65 armature through the medium of which said

control is exercised sometimes by the magnet holding the armature against the pole piece and sometimes by releasing the armature, and means independent of the magnet for causing the armature to periodically advance against the pole piece. 70

5. In an arc lamp having a pair of electrodes, a feed mechanism for one of the electrodes of the lamp, a driving element for said feed, means for driving said feed from the 75 said driving element and independent means for driving said feed from the same driving element, and electromagnetic means adapted to be energized from a source of potential for throwing said independent means into operative condition whereby the feeding operation of the electrode through said independent means may be carried on, said electromagnetic means adapted also, when the voltage at said source drops below a certain 80 point, to become deenergized sufficiently for throwing said independent means out of operative condition, whereby the feeding of the electrode through said independent means 85 may be terminated. 90

6. In an arc lamp having a pair of electrodes, a feed mechanism for one of the electrodes of the lamp, a driving element for said feed, means for driving said feed from the said driving element and independent means for driving said feed from the same driving element, an electromagnetic means adapted to be energized from a source of potential for throwing said independent means into operative condition whereby the feeding operation of the electrode through said independent means may be carried on, said electromagnetic means adapted also, when the voltage at said source drops below a certain point to become deenergized sufficiently for throwing said independent means out of operative condition, whereby the feeding of the electrode through said independent means 95 may be terminated, said electromagnetic means comprising an adjustable element for varying the range of action of said electromagnetic means responsive to the variation in said voltage. 105

7. In an arc lamp having a pair of electrodes, a feed mechanism for one of the electrodes of the lamp, a driving element for said feed, means for driving said feed from the said driving element and independent means for driving said feed from the same driving element, an electromagnetic means adapted to be energized from a source of potential for throwing said independent means into operative condition whereby the feeding operation of the electrode through said independent means may be carried on, said electromagnetic means adapted also when the voltage at said source drops below a certain point, to become deenergized sufficiently for throwing said independent means out of operative condition, whereby the feeding of 110 115 120 125 130

the electrode through said independent means may be terminated, and means for preventing the electromagnetic means, when deenergized, from throwing said independent means out of operative engagement

5 whereby the feeding operation of the electrode may persist even though the electromagnetic means be deenergized.

8. In an arc lamp, a fast feed mechanism, 10 a slow feed mechanism, an arc drawing mechanism, and an electromagnet connected to be energized when current is flowing through the electrodes for throwing out the fast feed and for drawing the arc.

15 9. In an arc lamp, a pair of electrodes for maintaining the arc between them, an electromagnet connected to be energized when a flow of current is established through the electrodes, a feed mechanism for feeding one 20 of said electrodes fast and another for feeding the same electrodes slowly, a motor for operating said feeds, an arc drawing mechanism separate from the feed for separating one of the electrodes from the other to draw 25 the arc, the fast feed and the arc drawing mechanism being under the control of said electromagnet.

10. In an arc lamp, a pair of electrodes for maintaining an arc between them, an 30 electromagnet connected to be energized when current is flowing through the electrodes, a feed mechanism for feeding one of said electrodes fast and another for feeding the same electrode slowly, a motor for operating said feeds, an arc drawing mechanism 35 separate from the feed for separating one of the electrodes from the other to draw the arc whereby when the lamp is connected to a source of current while the electrodes are 40 separate both feeds are brought into opera-

tion by the motor until the electrodes strike, the electromagnet is energized, the fast feed stopped by the electromagnet and the arc drawn thereby and the slow feed left in operation.

45

11. In an arc lamp, an electrode feed mechanism, a driving element, means interposed between the driving element and the feed mechanism whereby the feed may be operated by said driving element, an electromagnetic device, said means under the control of said device whereby the feeding operation may be regulated, said device comprising an armature through the medium of which said control is exercised, means independent of the magnet for periodically forcing the armature against the pole piece, and means for rendering the control of said feed through said armature ineffective and at the same time maintaining the said interposed 60 means effective whereby the feeding operation may be continued without interruption by said armature.

12. In an arc lamp, an electrode feed mechanism, a driving element, means interposed between the driving element and the feed mechanism whereby the feed may be operated by said driving element, an electromagnetic device, said means under the control of said device whereby the feeding 65 operation may be regulated, said device comprising an armature through the medium of which said control is exercised, means independent of the magnet for causing the armature to periodically advance against the pole 70 piece.

In witness whereof, I have hereunto set my hand this 4th day of April, 1925.

EDWIN J. MURPHY.
